GRATE BAR

Walter C. Dilg, Floral Park, N. Y., assignor to
 Waugh Equipment Company, New York, N. Y.,
 a corporation of Maine

Application June 9, 1942, Serial No. 446,384

8 Claims. (Cl. 126—163)

This invention relates to grate bars for heavy duty purposes, as, for example, in locomotive fire boxes and boiler furnaces, and is concerned more particularly with a novel grate bar which is superior to prior grate bars of the same general type, in that it provides for more nearly uniform distribution of combustion air throughout the fuel bed and also reduces the liability of blow holes being formed through the fuel bed by the action of the draft. The new grate bar resembles in some respects that described and claimed in Thompson Patent No. 1,803,152, issued April 28, 1931, but is an improvement on the patented bar by reason of the inclusion of novel features, the use of which produces the better results mentioned.

The Thompson grate bar includes fuel-supporting units which are preferably mounted detachably on a carrier bar provided with trunnions by which it is supported on a grate frame. Each such unit comprises a plate-like body having spaced vertical lugs projecting from its opposite faces and defining passages through which combustion air flows upwardly from the ash pit. The top of each lug and the top of the body between aligned lugs on its opposite faces are subdivided into small fuel-supporting areas separated by air channels, some of which open into the passages between adjacent lugs and others of which lead to the outer faces of the lugs. Adjacent fuel-supporting units are kept at a suitable close spacing on the carrier bar by stop lugs on opposed faces of the units, and adjacent carrier bars are so mounted on the frame that the opposed ends of the fuel-supporting units on adjacent bars lie close together.

When fuel is burned on a grate formed of bars of the Thompson type, combustion air flows up from the ash pit to the fuel bed through the passages between adjacent lugs on each fuel-supporting unit, the spaces between aligned lugs on adjacent units on the same carrier bar, and the spaces between the opposed ends of units on adjacent carrier bars. Some of the air flowing upwardly from the ash pit to the fuel bed enters the channels and flows horizontally therein to parts of the fuel not directly over the passages and spaces. The air so supplied to the fuel through the channels thus changes direction in its flow from the ash pit to the fuel bed and may be termed "indirect air." The remainder of the air flowing directly upwardly to the fuel may be termed "direct air" and it is desirable that a substantial proportion of the air supplied for combustion be in the form of indirect air in order

that combustion of the fuel may be as nearly uniform and complete as possible.

In the Thompson bar, the plate or body of each fuel-supporting unit is of increasing thickness throughout the length of the passages and the lugs are of substantial length and also of increasing width upwardly. The passages are thus of decreasing cross-section upwardly and the air flowing through the passages under the pull of the draft attains substantial velocity by the time it reaches the fuel bed, so that there is less tendency for the air to flow laterally in the channels than is desirable. Also, when sudden heavy drafts are applied, as occurs frequently in locomotive operation, the air flowing upward through the unobstructed passages may produce blow holes through the fuel bed.

The present grate bar is so constructed as to provide improved combustion by reason of the fuel being supplied with an increased amount of air in indirect form and, with the new bar, the liability of blow holes being formed by the application of sudden heavy drafts to the fuel bed is lessened. These results are obtained by the provision of means which intercept the air streams flowing upwardly to the fuel and cause mingling and turbulence of the streams with resultant reduction in velocity and increased lateral flow.

For a better understanding of the invention, reference may be had to the accompanying drawings in which

Fig. 1 is a view showing a carrier bar in cross-section and one of the fuel supporting units thereon in front elevation;

Fig. 2 is a sectional view through a pair of adjacent fuel-supporting units 2—2 of Fig. 3;

Fig. 3 is a fragmentary plan view of the units shown in Fig. 2; and

Fig. 4 is a view of a carrier bar in side elevation and shows the manner in which the units may be applied thereto and removed therefrom.

The grate bar in the form illustrated is of the type which includes a carrier bar and a number of cross bars or fuel-supporting units detachably mounted thereon, but it is to be understood that the units may be formed integrally with the carrier bar, if desired. The carrier includes a web 10 and a longitudinal flange 11 extending upwardly therefrom and the web is provided at its ends with arms 12 from which project trunnions 13. Mounted detachably on the carrier are fuel-supporting units, each of which includes a plate-like body 14 which is formed at its lower end with an opening 15 of the same general shape as the cross-section of the carrier. At the lower ends

of the opening are lugs 16 and to mount a unit on the carrier, the unit is placed in the inclined position shown at the left in Fig. 4 and lowered with the lugs passing on opposite sides of the trunnion arm, until the lugs pass beyond the end of the web 10. To facilitate this operation, the web may be cut away as indicated at 17. When the lugs lie below the level of the web, the unit is swung to upright position and moved along the web. The unit then rests on the inclined upper surfaces 18 of the web on either side of the flange and the unit cannot be accidentally dislodged from the bar because the ends of the lugs underlie the lateral edges of the web.

Projecting outwardly from opposite faces of the body at its upper end are lugs 19, and the bottom of each lug slopes downwardly at an angle to the face of the body and is formed of a pair of surfaces 21 diverging upwardly from a median line 22. The top of each lug is subdivided into four small fuel-supporting areas 23 by air channels 24, 25, the channels 24 opening at the outer faces of the lugs and channels 25 leading to the passages defined by adjacent lugs. Between adjacent lugs, the top of the body is of decreasing thickness upwardly, as indicated at 26, so that the stream of air flowing through the passage between the lugs may flow over the top of the body to fuel lying directly over the body. The top of the body is also channeled, as indicated at 27, between aligned lugs on opposite faces of the body, so that air flowing up through the passages between adjacent lugs may enter channels 27 and reach fuel lying directly above the body.

Mounted on the faces of the body in alignment with and spaced downwardly from the lower ends of the passages between adjacent lugs are projections 28. The upper ends of the projections slope upwardly and inwardly toward the body and have surfaces 29 which converge upwardly to meet in a median line 30.

The end lug 31 on each face of the body has a portion 32 which extends down along the end of the body and has a flat bottom. The inward side of the extension 32 slopes upwardly and inwardly and leads to a surface 33 which inclines upwardly and inwardly and leads to the air passage between the end lug and that next to it.

At the middle of each face of the second supporting unit, there is a single double lug 34 employed to give the unit additional strength at the place where it would otherwise be weakened by removal of the metal to form the opening in which the carrier is received. The lug 34 is provided on its sides with projections 35 which have inwardly sloping upper surfaces 36 lying directly beneath the passages 37 between lug 34 and the adjacent lugs outwardly therefrom.

The lugs 28 project outwardly from the face of the body a distance slightly greater than lugs 19 and, when a plurality of fuel-supporting units are mounted on a carrier, lugs 28 on adjacent units make contact and serve as means for keeping the adjacent units at the desired spacing.

In the combustion of fuel on a grate made up of the new bars, the fuel is supported on the top of the small areas 23 and part of the air supplied by the fuel flows upwardly along the faces of the units in each passage between a pair of lugs 28. The air flowing through this space cannot flow directly to the fuel, however, but is intercepted by the under surface of a lug 19 above the space between adjacent lugs 28 and is subdivided into two streams by the inclined surfaces

21 on lug 19. Each portion of the stream then flows toward a passage between adjacent lugs 19 and meets air diverted toward that passage by part of the under surface of the adjacent lug 19. The air streams mingle with a turbulent action and the resultant stream flows upwardly through the air passage and also inwardly along the sloping surface of the portion 26 of the body. By reason of the change in direction of flow of the air just before it enters a passage between adjacent lugs 19 and of the decreasing thickness of the body at 26, the velocity of the air flow is reduced so that proper flow of air into the channels 25 and 27 is insured. Some air flows upward through the spaces 38 between the ends of the aligned lugs on adjacent units, but, as these passages are relatively narrow and of decreasing cross-section, as shown in Fig. 2, the tendency is for the greater proportion of the air to flow laterally along the surfaces 21 on lugs 19 and then upwardly through the passages between adjacent lugs 19. Additional air also flows upwardly through the spaces between the ends of aligned units on adjacent carrier bars, but ordinarily the carrier bars are mounted so that such aligned units lie relatively close together and the amount of air flowing through the spaces between such units is less than that flowing between adjacent units on the same carrier.

30 The formation of the units with portions 26 of tapering thickness between adjacent lugs 19 is advantageous not only in the distribution of air, as above pointed out, but also in preventing collection of ash. The sides of these portions are relatively steep and there is little likelihood that ash will accumulate thereon. Also, the tops of the lugs 28 slope downwardly at a relatively steep angle and that, together with the formation of the tops with the opposite sloping surfaces 29, likewise tends to prevent ash accumulation.

I claim:

1. A grate structure comprising a carrier bar and a plurality of cross bars mounted thereon and extending transversely thereof, each cross bar having a plurality of lugs extending from opposite faces at the top and spaced to provide air passages between them, the lugs on the opposite faces of each cross bar being in alignment and the cross bars being mounted on the carrier bar with the spaced lugs of one cross bar being in alignment with the spaced lugs of adjacent cross bars, and a plurality of projections from the opposite faces of the cross bars lying in alignment with and spaced from the lower ends of the air passages, the outer ends of the projections lying outwardly beyond the ends of the lugs and the outer ends of the projections of one cross bar engaging the outer ends of the corresponding projections of adjacent cross bars to space the outer ends of corresponding lugs of adjacent cross bars to provide air passages between them.

2. A grate structure comprising a carrier bar and a plurality of cross bars mounted thereon and extending transversely thereof, each cross bar having a plurality of lugs extending from opposite faces at the top and spaced to provide air passages between them, the lugs on the opposite faces of each cross bar being in alignment and the cross bars being mounted on the carrier bar with the spaced lugs of one cross bar being in alignment with the spaced lugs of adjacent cross bars, and a plurality of projections from the opposite faces of the cross bars lying in alignment with and spaced from the lower ends of the air passages, the outer ends of the projections lying

outwardly beyond the ends of the lugs and the outer ends of the projections of one cross bar engaging the outer ends of the corresponding projections of adjacent cross bars to space the outer ends of corresponding lugs of adjacent cross bars to provide air passages between them, said projections being of a width not substantially less than the width of the lower end of the passages between adjacent lugs on a cross bar so that most of the air passing upwardly through those passages will be caused to flow around opposite sides of the projections and to enter those passages at a converging angle.

3. A cross bar for a grate structure having a plurality of lugs extending from its opposite faces at its top and spaced along the body to provide air passages between them, the lugs on opposite faces of the cross bar being in alignment transversely, the thickness of the body of the cross bar between the lugs decreasing upwardly to increase the cross-sectional area of the air passages between the lugs toward their upper ends, and a plurality of projections from the opposite faces of the cross bar lying in alignment with and spaced from the lower ends of the passages.

4. A cross bar for a grate structure having a plurality of lugs extending transversely therefrom at opposite faces at the top thereof, the lugs on opposite faces of the cross bar being in alignment, the tops of the lugs and the tops of the portions of the body of the cross bar between the aligned lugs being channeled to substantially divide the upper surface of the unit into small fuel-supporting surfaces, the lugs on each face of the body being spaced to provide air passages between them leading to the channels, and a projection from the face of the cross bar lying in alignment with and spaced from the lower end of each air passage, said projections being of a width not substantially less than the width of the lower end of the air passages so that most of the air to enter said passages from beneath the cross bar will be caused to flow around opposite sides of said projections and to enter the passages at a converging angle.

5. A cross bar for a grate structure having a plurality of lugs extending transversely therefrom at opposite faces at the top thereof and spaced to provide air passages between them, the lugs on opposite faces of the cross bar being in alignment, and projections from the opposite faces of the cross bar lying in alignment with and spaced from the lower ends of the air passages, said projections being of a width not substantially less than the width of the lower ends of the air passages so that most of the air to enter said passages from beneath the cross bar will be caused to flow around opposite sides of said projections and to enter the passages at a converging angle.

6. A cross bar for a grate structure having a plurality of lugs extending transversely therefrom at opposite faces at the top thereof and spaced to provide air passages between them, the lugs on opposite faces of the cross bar being in alignment, and projections from the opposite faces of the cross bar lying in alignment with and spaced from the lower ends of the air passages, the projections having downwardly and outwardly sloping top surfaces, said projections being of a width not substantially less than the width of the lower ends of the air passages so that most of the air to enter said passages from beneath the cross bar will be caused to flow around opposite sides of said projections and to enter the passages at a converging angle.

7. A cross bar for a grate structure having a plurality of lugs extending transversely therefrom at opposite faces of the top thereof and spaced to provide air passages between them, the lugs on opposite faces of the cross bar being in alignment, the bottoms of the lugs sloping outwardly and upwardly and being provided with surfaces which diverge upwardly, and projections from the opposite faces of the cross bar lying in alignment with and spaced from the lower ends of the air passages, the top of each projection sloping upwardly and inwardly and being provided with surfaces which converge upwardly, said projections being of a width not substantially less than the width of the lower ends of the air passages so that most of the air to enter said passages from beneath the cross bar will be caused to flow around opposite sides of said projections and to enter the air passages at a converging angle.

8. A cross bar for a grate structure having a plurality of lugs extending transversely therefrom at opposite faces of the top thereof and spaced to provide air passages between them, the lugs on opposite faces of the cross bar being in alignment, the bottoms of the lugs sloping outwardly and upwardly and being provided with surfaces which diverge upwardly, and projections from the opposite faces of the cross bar lying in alignment with and spaced from the lower ends of the air passages, the top of each projection sloping upwardly and inwardly and being provided with surfaces which converge upwardly, the opposite faces of the cross bar between adjacent lugs sloping inwardly, said projections being of a width not substantially less than the width of the lower ends of the air passages so that most of the air to enter said passages from beneath the cross bar will be caused to flow around opposite sides of said projections and to enter the air passages at a converging angle.
